UNITED STATES PATENT OFFICE.

PIERRE BESANCON DE WAGNER, OF PARIS, FRANCE.

DESIGN FOR A BOTTLE.

Application filed February 25, 1926. Serial No. 16,658. Term of patent 7 years.

To all whom it may concern:

Be it known that I, PIERRE BESANCON DE WAGNER, a citizen of the Republic of France, residing in the city of Paris, France, have invented a new, original, and ornamental Design for a Bottle, of which the following is a specification, reference being had to the accompanying drawing, forming a part thereof.

In the drawing:

I claim:

The ornamental design for a bottle substantially as shown.

PIERRE BESANCON DE WAGNER.
